Inventor:
Herman C. Pribe
By A. L. Brooks

UNITED STATES PATENT OFFICE.

HERMAN C. PRIEDE, OF BLUE ISLAND, ILLINOIS.

DRAFT-GEAR.

1,282,938.

Specification of Letters Patent. Patented Oct. 20, 1916.

Application filed July 19, 1916. Serial No. 110,015.

To all whom it may concern:

Be it known that I, HERMAN C. PRIEDE, citizen of the United States, residing at Blue Island, in the county of Cook and State of Illinois, have invented a certain new and useful Improvement in Draft-Gears, of which the following is a full, clear, concise, and exact description, reference being had to the accompanying drawings, forming a part of this specification.

My invention relates to draft gears and has a number of objects and advantages in view. In accordance with one feature of my invention I constitute the inner end of a coupler a friction producing follower that operates upon the balance of the gear to produce friction and to enable spring mechanism to resist inward motion of the coupler.

My invention, in another of its aspects, relates to those friction draft gears which employ rockers having opposed engaging faces that operate upon the spring mechanism to resist motion and in practising this feature of my invention I cause the spring mechanism to receive initial impacts so that the tips of the rockers may not be suddenly brought into forceful engagement which would wear them away and would be likely to cause breakage. The means which I desirably employ for enabling the spring mechanism to cushion the initial impact to relieve the tips of the rockers of impacts are desirably also employed to tie the rockers together to prevent their separation in the event of breakage of the gear.

I will explain my invention more fully by reference to the accompanying drawings showing the preferred embodiment thereof and in which Figure 1 is a longitudinal sectional view of enough of a car structure to illustrate my draft gear invention; Fig. 2 is a view on line 2—2 of Fig. 1; Fig. 3 is a view on line 3—3 of Fig. 2; Fig. 4 is a perspective view of a coupler yoke as it is preferably formed; and Figs. 5, 6 and 7 are perspective views of different portions of the draft gear structure.

Like parts are indicated by similar characters of reference throughout the different figures.

The coupler 1 includes a shank 2 which is connected with a yoke structure in a manner later to be set forth, the sides of the illustrated yoke structure being in the form of straps 3 through which openings 4 and 5 are provided for the reception of keys 6 and

7, the former of which constituting a structural part of the outer follower. The openings permit the keys to move inwardly with respect to the yoke when the coupler is subject to a sufficient pushing strain. The aforesaid keys also project through openings 8 and 9 in the cheek plates 10 and 11 which are secured to the center sills 12 and 13, the openings 9 registering with the openings 5 and corresponding openings in the center sills when the gear is not under stress, the openings 8 similarly registering with the openings 4 and similar openings in the center sills. Cotter pins 14 may be employed to prevent the withdrawal of the keys from the slots in the center sills that receive them.

The outer follower 15 has an offsetting cylindrical stem 16 which is co-axial with the coupler shank and passes through a hole in said shank, this hole being preferably of larger diameter than the stem so that the follower 15 may universally swing with respect to the stem during the various swinging movements of the coupler shank. The follower 15 has an opening therethrough through which the draft gear supporting key 6 is slipped, this follower 15 thus surrounding said key, the slot being of sufficient size to permit of the movement of the key in said follower and transversely to the gear. The inner follower 17 desirably has a similar semi-cylindrical portion at its front end, this follower desirably also constituting a web that unites the inner ends of the side yoke straps 3, being desirably integrally formed with said straps. I desirably also provide, as an integral part of the yoke structure, the extension 18 that is received in a correspondingly shaped slot formed in the bifurcated portion 19 of the web 20 in the back stop 21 that is secured to the center sills.

The curved or semi-cylindrical portions 100 of the outer follower 15 and the inner follower 17 extend transversely of the gear and horizontally, it being believed that it is broadly new thus to direct the curvature of the inner end of the outer follower. The 105 opposed rounded faces of the forward and rear followers are received within semi-cylindrical pockets 22, 23 that are formed in the stems of rockers 24, 25, there being outwardly diverging arms 26, 27, 28 and 110 29 between which the elements 15 and 17 are disposed. The rockers have direct en-

gagement with each other and the opposed faces thereof are curved or cam-shaped so that each rocker will co-act with the other and serve as a resistance therefor to force 5 the rockers to swing in a vertical plane upon coupler movement. The motion resisting mechanism shown includes a spring structure having a plurality of vertically disposed coiled springs 30 that are located 10 above the rockers and whose upper ends bear against a common seat 31 that is secured to the tops of the center sills. The lower ends of these vertical coiled springs 30 are provided with seats or pockets 32 in the 15 common spring seat 31.

In accordance with another feature of my invention the springs serve to cushion the blow of each rocker upon the other when the rockers are initially brought into action 20 upon each other at their upper ends whereby breakage and flattening of the upper ends of the rockers are guarded against. One means for carrying this object into effect is shown in the drawings. To this 25 end I employ the spanner 33 which engages heavier portions 34 of the rockers, this spanner serving to keep the points 35 of the rockers out of forceful engagement when the rockers are approaching one another, 30 whereby forceful engagement does not occur between the rockers until the more solid portions thereof are in engagement. The spanner also co-acts with the upper portions 35 of the rocker structures to press upon the spring bed 32 and against the force of the springs 30 before the faces of the rockers are brought into effective engagement. Thus the spring mechanism serves to take the 40 initial blows and to relieve the points of the rockers from the force of the initial blows and to reduce the force of the initial engagement of the rockers. The spanner desirably also has such interengagement with the rockers that it will prevent the rockers 45 from coming apart in the event of breakage of the gear. This interengagement is desirably effected by bolts 36 that pass loosely through the depending ears at the ends of the spanner 33 and the lugs 37 in the upper 50 portions of the rockers.

There is no appreciable frictional engagement between the engaging opposed faces of the rockers, the rockers thus coöperating with the spring mechanism to afford spring 55 resistance to mutual approaching movements of the followers and while the rockers are preferably formed and operate in accordance with my prior inventions I do not wish to be limited to such an operation in 60 the practice of my present invention.

I supplement the spring action of the gear by means of the friction produced by the rolling action of the rockers upon the large forward and rear followers. Friction also 65 occurs between the ends of the spanner 33 and

the portions of the rockers engaging these ends and also between the top faces of this spanner and the bottom of the spring seat 32.

While I have herein shown and particularly described the preferred embodiment of 70 my invention I do not wish to be limited to the precise details of construction shown as changes may readily be made without departing from the spirit of my invention, but having thus described my invention I claim 75 as new and desire to secure by Letters Patent the following:—

1. A draft gear including a coupler; inner and outer followers actuated thereby; means for resisting the approach of either 80 follower toward the other; two rockers operating in conjunction with the aforesaid means, each follower having a rocker in engagement therewith and each rocker having a curved face for engagement with the 85 curved face of the other rocker in the operation of the gear; and means for reducing the force of the initial action of the rockers upon each other.

2. A draft gear including a coupler; inner 90 and outer followers actuated thereby; means for resisting the approach of either follower toward the other; two rockers operating in conjunction with the aforesaid means, each follower having a rocker in engagement therewith and each rocker having a curved face for engagement with the 95 curved face of the other rocker in the operation of the gear; and means for enabling the aforesaid means to reduce the force of the 100 initial action of the rockers upon each other.

3. A draft gear including a coupler; inner and outer followers actuated thereby; spring mechanism for resisting the approach of either follower toward the other; two 105 rockers operating in conjunction with the aforesaid spring mechanism, each follower having a rocker in engagement therewith and each rocker having a curved face for 110 engagement with the curved face of the other rocker in the operation of the gear; and means for reducing the force of the initial action of the rockers upon each other.

4. A draft gear including a coupler; inner and outer followers actuated thereby; 115 spring mechanism for resisting the approach of either follower toward the other; two rockers operating in conjunction with the aforesaid spring mechanism, each follower having a rocker in engagement therewith and each rocker having a curved face for 120 engagement with the curved face of the other rocker in the operation of the gear; and means for enabling the aforesaid spring mechanism to reduce the force of the initial 125 action of the rocker upon each other.

5. A draft gear including a coupler; inner and outer followers actuated thereby; spring mechanism for resisting the approach of either follower toward the other; two 130

rockers operating in conjunction with the aforesaid spring mechanism, each follower having a rocker in engagement therewith and each rocker having a curved face for engagement with the curved face of the other rocker in the operation of the gear; and a spanner disposed between said rockers and operating upon the spring mechanism to reduce the force of the initial action of 10 the rockers upon each other.

6. A draft gear including a coupler; inner and outer followers actuated thereby; means for resisting the approach of either follower toward the other; two rockers op-

erating in conjunction with the aforesaid 15 means, each follower having a rocker in engagement therewith and each rocker having a curved face for engagement with the curved face of the other rocker in the operation of the gear; and a spanner tying the 20 rockers together to secure them in assembly.

In witness whereof, I hereunto subscribe my name this fourteenth day of July, A. D., 1916.

HERMAN C. PRIEBE.
